UNITED STATES PATENT OFFICE.

CHARLES T. GARDNER, OF NEW YORK, N. Y., ASSIGNOR TO AJAX RUBBER COMPANY, INC., OF MILLBROOK, NEW YORK, A CORPORATION OF NEW YORK.

DESIGN FOR A TIRE-TREAD.

59,075.

Specification for Design.

Patented Sept. 20, 1921.

Application filed April 2, 1921. Serial No. 458,046. Term of patent 14 years.

To all whom it may concern:

Be it known that I, CHARLES T. GARDNER, a citizen of the United States, and resident of the borough of Bronx, in the city and State of New York, have invented a new, original, and ornamental Design for a Tire-Tread, of which the following is a specification, reference being had to the accompanying drawing, forming part thereof.

My new design for a tire tread is shown in the accompanying drawing, in which,

Figure 1 represents a plan view of a portion of a tire casing.

Fig. 2 represents a side elevation of the same.

Fig. 3 represents a transverse section taken in the plane of the line III of Fig. 1, and

Fig. 4 represents a transverse section taken in the plane of the line IV of Fig. 1.

I claim:

The ornamental design for a tire tread, substantially as shown.

CHARLES T. GARDNER.
